DISPLAY STAND

Filed Aug. 11, 1930

FIG. 1.

FIG. 2.

UNITED STATES PATENT OFFICE

HENRY F. GOULET, OF WALPOLE, MASSACHUSETTS

DISPLAY STAND

Application filed August 11, 1930. Serial No. 474,575.

This invention relates to grocers' display stands of that general type described in my prior Patent No. 1,733,406 and dated October 29, 1929.

An object of the present invention is to provide a display stand having a plurality of superposed trays arranged in stepped relationship for holding boxes of vegetables or the like at such an angle that their contents may be attractively displayed, skeleton covers being provided for concealing the boxes so that the stand is attractive in appearance, only the contents of the boxes being exposed to view.

A further object of the invention is to provide novel covers for the trays, each cover comprising a front and side wall, there being a longitudinal angle iron strip connecting the side walls and coacting with transverse flat strips connected to the longitudinal strip and to a marginal flange on the front wall to conceal the top edges of the wood boxes which contain the vegetables or like articles on display and at the same time perform the function of shields which prevent the customer's fingers from being injured by contact with rough wooden boxes, as sometimes occurs where rough edges of display boxes are fully exposed.

A still further object of the invention is to provide an all metal display stand which will be light in weight and inexpensive to manufacture and preferably will be mounted on castors so as to be easily moved from place to place.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a perspective view of a display stand constructed in accordance with my invention,

Fig. 2 is a cross sectional view through the display stand, and

Fig. 3 is a detail perspective view of one of the skeleton covers.

Referring now to the drawings in which like characters of reference designate similar parts, the display stand is shown to comprise sheet metal side walls 10, each of which is provided with a marginal flange all around the edge thereof, as shown at 11, to strengthen the wall against distortion. Each wall is cut away obliquely at the front edge, as shown at 12. Castors 13 are secured to the marginal flange of each wall at the front and rear corners thereof.

A plurality of trays 14, each formed of sheet metal are arranged in superposed relationship between the side walls 10 and are stepped rearwardly as the trays progress in number from the bottom to the uppermost tray, as clearly shown in Fig. 2. Each tray is, furthermore, set at an angle of about 30° from the horizontal. Each tray is formed with a marginal flange 15 disposed along the entire peripheral edge of the tray and adapted to extend upwardly along and confine a plurality of wood boxes 16, preferably three in number, on the tray. The side flanges of the tray are riveted, as shown at 16, to the side walls 10 of the stand.

The side walls of the stand are further strengthened to resist distortion when the trays are loaded with boxes of vegetables or the like, and for this purpose a channel iron transverse brace 17 is secured to the rear flanges of the side walls near the bottoms of the side walls, as best shown in Fig. 2. Inclined braces 18 are riveted or otherwise secured to the channel iron brace 17 and to the rear upturned flange of the uppermost tray, as shown at 19 and 20 in Fig. 2.

Preferably an additional tray 21 is secured by angle iron braces 22 and 23 to the side walls above the uppermost inclined tray. This tray extends horizontally and may be utilized as a shelf for storing articles in packages if desired.

In order that the rough woodwork of the vegetable boxes will be concealed from view and also the customers' hands will be protected from slivers and the like, I provide skeleton covers 24 for the trays, as best shown

in Fig. 3. Each cover is preferably formed of sheet metal and comprises a front wall 25 and side walls 26, said front and side walls being provided at the top with inturned flanges 27 and 27'. An angle iron brace 28 is riveted or otherwise secured to the flanges 27' of the side walls at the rear ends thereof and extends longitudinally of the cover. Flat metal strips 29 are arranged substantially equi-distant apart transversely of the cover and are riveted or otherwise secured at the ends to the angle iron brace 28 and to the flange of the front wall.

When the cover is applied to a tray loaded with for instance three boxes of vegetables, the transverse strips 29 bridge the top edges of the side walls of each two adjoining boxes. The flanges 27 and 27' and the angle iron brace 28 fit over the top outer edges of all of the boxes. Thus the top edges of the boxes are concealed from view. The front walls of all of the boxes are concealed by the front wall 25 of the cover and the side walls 26 of the cover conceal the side walls of the end boxes.

Obviously, only the vegetables or other articles on display in the boxes are exposed to view and may be safely removed by the customers without danger of injury to the fingers since the flanges 27 and 27', transverse strips 29 and longitudinal brace 28 form shields which protect the fingers from contact with the boxes 16.

Preferably the front wall 24 of each skeleton cover is equipped with a plurality of frames 30 corresponding in number to the number of boxes 16 and which receive price tags 31 or other descriptive matter referring to the contents of the respective boxes.

40 In order that seepage from the vegetable boxes when the vegetables are wet may be drained from the device, a drain pipe 32 is preferably attached to one side wall of the display stand on the inner face thereof. The 45 drain pipe is provided with a plurality of openings 33 which open through the walls of the trays, as best shown in Fig. 2. The trays being inclined permit of the water accumulating at the lower end thereof and escaping 50 through the openings 33 in the drain pipe.

Having thus described the invention, I claim:

1. A display stand comprising spaced sides, a tray secured to said sides and adapted to hold a row of display boxes, a cover for the tray having walls adapted to conceal the walls of the boxes, and transverse strips carried by the front wall of the cover and adapted to conceal the contiguous top edges of adjoining display boxes.

2. A display stand comprising spaced sides, a tray secured to said sides and adapted to support a row of display boxes, said tray having a marginal flange around its periphery, and a cover fitting within said mar-

ginal flange and having, flanges, transverse strips, and a longitudinal brace adapted to conceal all of the top edges of said display boxes.

3. A display stand comprising sides, a forwardly sloping tray secured to said sides and having an upstanding marginal flange, said tray being adapted to support a row of display boxes, and a skeleton cover for the tray comprising front and end walls receivable within the marginal flange of said tray, said walls having inturned flanges at the top thereof, a longitudinal angle iron brace secured to said end walls at the top thereof, and transverse strips secured to said brace and to the flange of said front wall, said strips being adapted to conceal the contiguous edges of adjoining display boxes, said longitudinal brace coacting with the flanges of said front and end walls to conceal the remaining top edges of the boxes.

4. A display stand comprising spaced sides, a plurality of inclined superposed trays for supporting rows of display boxes, said trays being arranged in stepped relation, and skeleton covers for the trays each comprising front and end walls, a longitudinal brace, and transverse strips connecting said front wall with said brace, said front and end walls having flanges at the top, said longitudinal brace and said transverse strips coacting therewith in concealing the top edges of all of the display boxes.

5. A display stand comprising spaced sides, a plurality of inclined superposed trays for supporting rows of display boxes, each tray having an upstanding flange around the periphery thereof, the lateral portions of said flange being rigidly secured to said sides of the stand, and skeleton covers for the trays receivable within the peripheral flanges thereof each comprising a front wall, end walls, said walls having inturned flanges at the top thereof, a longitudinal angle iron brace connecting said end walls, and transverse strips connecting said longitudinal brace with the flange of said front wall, said strips being adapted to conceal the contiguous top edges of adjoining boxes of the row of display boxes, said inturned flanges of the front and side walls coacting with said angle iron longitudinal brace in concealing the remaining top edges of all of the boxes of the row of boxes.

In testimony whereof I affix my signature.
HENRY F. GOULET. [L. s.]
